ELECTRICAL HEATED IRON

Stanley Alexander Duvall, Louisville, Ky., assignor of one-half to Laura V. Ruffin, Louisville, Ky.

Application December 30, 1932, Serial No. 649,605

4 Claims. (Cl. 219—25)

My invention relates to electric smoothing irons and has for its object the production of an electrically heated hand iron and stand so arranged and so related that the cord carrying current for heating the iron shall terminate at the stand and the iron per se shall be cordless; and in which the iron is related to the stand by means of a plate and spring jack connections so arranged that the iron need never be lifted but can be slid on and off the said plate to engage and disengage its terminal plugs with the spring jacks and to pass on and off of the object to be pressed. In attaining my objects I provide a housing containing terminals for the energizing circuit, spring jacks to receive plugs on the iron constituting terminals of the heating element resistors, and a thermostat mounted near the heel of the iron when the latter is on the stand. Carrying this housing and extending out therefrom on the same side as the spring jacks is a metal plate carrying an insulating sheet which may be of asbestos or any other suitable heat insulating material. One of the most important features of my invention is the sliding movement of the iron on and off this plate and another the saving of electric current, and the elimination of sparking and flashing at the contacts, as well as the primary feature of the elimination of any cord to drag over the work, in the manner described by my resting plate. The heat insulation of the plate is so arranged that its surface meets flush with the cloth wrappings of the ironing board and various other details of more or less importance to the combination will sufficiently appear from the detailed specification herein-after.

My invention is illustrated in the accompanying drawings, in which

Fig. 1 is a side view of one end of an ironing board showing the iron on the resting plate with the housing partly in section;

Fig. 2 is a plan view of the parts shown in Fig. 1;

Fig. 3 is a cross section on the line 3—3 of Fig. 2 looking in the direction of the arrows;

Fig. 4 is a rear elevation of the housing and clamp for securing the apparatus to the board; and

Fig. 5 is a diagram showing the electrical connections in the housing and in the iron.

In the drawings and referring first to Figs. 1 and 2, B is an ironing board shown as covered with a suitable cloth. I represents a hand iron having heating plate 2 enclosing a heating element 3 consisting of coils of resistance wire or the

equivalent electrically insulated. At the heel of the iron, above the heating plate, I provide a pair of terminal plugs 16a and 16b for the heating element.

6 represents a housing composed of a metal 5 cover plate or bridge with a back end and front end 7 and 8 respectively of hard fiber or equivalent insulation. The sides and top of the cover plate are in one piece which may conveniently be of Monel metal of about No. 20 B & S gauge 10 secured to the fiber end pieces, which are about one-half inch thick. The end piece 7 is provided with an opening 1c and the end piece 8 similarly provided with an opening 8c. Enclosed entirely within the housing is an insulating block carried 15 on a metal bridge extending over the opening 1c. In this block are mounted jack springs 10 and 11 having their front ends extending forward into openings 8a and 8b in the front end piece 8, in position to engage the plugs 16b and 16a on the 20 iron when the latter is in resting position on the resting plate. The rear ends of the jack springs as stated extend through the insulating block in the openings 1a and 1b (see Fig. 4), which receive the terminals of the plug 9 connected by 25 a suitable cord with a source of electrical supply.

Adapted to rest upon the ironing board as shown in Figs. 1, 2, 3 and 4 and carrying the housing on one end and adapted to receive and carry the iron on the front end is the resting plate 4 which 30 is covered as to the end which receives the iron with a sheet of asbestos or equivalent heat insulating material 5, beveled off at its front edge 13 to permit easy sliding on and off of the iron 1, as clearly shown in Figs. 1 and 2. The plate 35 4 may conveniently be made of stainless iron sheet metal of No. 16 gauge about six inches wide and eleven inches long. This plate carrying all the other parts is held to the ironing board by means of a clamp 14 provided with a thumb 40 screw 14c and projecting studs 14a and 14b on its upper face which engage in registering openings in the rear end of the rest plate 4 beneath the bridge which carries the insulating plug in the housing.

During the use of the iron the opening 8c is left unstopped so that there may be free ventilation through it and the opening 1c to cool the parts between heating periods. When the iron is on the resting plate, however, the rear end of the heating 50 plate 2, as shown in Fig. 1, engages the edges of, and completely closes, the opening 8. By this means, heat is conserved while the current is on, with a resultant substantial saving in current. In order to render the economy more marked and 55

also to protect the iron from overheating, I provide a thermostat 18 which I locate as near as possible to the heel of the iron when in the position shown in Fig. 1. As a matter of convenience, 5 in the drawings the thermostat is shown to one side of and extending above the jack springs 10, but it should be clearly understood that the actual location of the thermostat may be beneath the spring or elsewhere to make close contact with 10 the heel of the iron. To this extent, the showing in Figs. 1 and 5 is diagrammatic.

For the purpose of guiding the iron over the insulating sheet 5 so that its plugs 16a and 16b will automatically engage with the jack springs 10 and 11 through the openings 8a and 8b in the end plate 8, and also for the purpose of holding down the asbestos sheet 5, I provide two metal guides and clamps 12. These are not shown in Fig. 1 which is partly in section, but they are 20 clearly shown in Figs. 2, 3, and 4.

In addition to the jack springs and the thermostat I locate within the housing a pair of resistors 15 which are included as shown in Fig. 5 in circuit with the long jack springs 10. As these 25 are the first to make contact with the plugs 16a and 16b on the iron, the initial circuit when the iron is pushed on the resting plate will be through the resistors which thus take up the initial surge of current as well as the formation of a destructive arc when the iron is slid off.

The circuit diagram of the iron and associated apparatus is shown in Fig. 5. Here the heating element 3 is shown as composed of resistance wires 17 terminating at their ends in the plugs 35 16a and 16b. The housing and the parts therein it is thought can be clearly understood as to their electrical connections from the previous description and the drawings. The following details however may be found useful in practicing 40 the invention: I make use of a standard type of the latest modern cord electric iron used with changes described in the contact parts. The cord and connection are changed and the plug and cord on the iron are removed. 16a and 16b are 45 well insulated heavy copper or brass terminal lugs and contact points. They are of great current carrying capacity, thus helping to reduce flashing when contacts are made and broken. The heating element 17 may be of any suitable resistance. The best known to me at the present time and for my purposes is as follows:

110 volt-heating element hot—20.4 ohms
110 volt-heating element cold—19.3 ohms
55 220 volt-heating element hot—81.6 ohms
220 volt-heating element cold—73.3 ohms

The resistors 15 may be 40 ohms or more in resistance. They are wound to sufficient capacity No. 28 B & S gauge to temporarily carry current 60 of 110 volts and 600 watts, or approximately 5½ amperes.

The jack springs 10 and 11 are of about No. 18 B & S gauge, brass spring metal, long and flexible.

The operation of my device is as follows: When 65 the iron is moved backward on to the plate 4 and the asbestos 5 as indicated in dotted lines in Fig. 2, the terminals 16a and 16b start to engage the jack springs 10 and 11, the first contact being made with the outside spring 10. Assuming the 70 plug 8 to be in place and the jack springs thereby to be connected to the electric light circuit outlet, current will start to flow through jack spring 10 to a resistor 15 and the thermostat, then through the plug 16a to the resistance element 11, 75 then out through the plug 16b, the other long

jack spring 10 and its resistor 15 to the cord plug 9 and back to the electric light circuit. As the iron reaches its final position to be heated as shown in Figs. 1 and 2, the plugs 16a and 16b make contact with springs 11 whereby the resistors 15 are shunted out of circuit. Current then flows through the resistance element 17 until the temperature of the iron has reached the predetermined maximum to which the thermostat 18 is set. At this point, the thermostat operates to 10 open the energizing circuit. The heat induced in the iron and in the parts within the housing is conserved because the opening AC is closed by the heel of the iron as shown in Figs. 1 and 2. If the iron cools to below the working temperature before being taken again for use, the thermostat will again close to reheat the iron. Thus the whole action of the apparatus is automatic besides being free from all risk of overheating or damaging either the ironing board or the apparatus itself. It should be well noted in addition, 20 that the design and construction of the housing and of the iron itself are such as to protect the hands of the operator at all times and to protect the iron and other parts from any loss of heat. 25 I assume that by the use of this apparatus I increase the output of work 30% and decrease the amount of current required by a similar percentage. The iron is never lifted by the operator. The iron easily slides on and off of the heat insulated plate to and from the ironing board. The plate is provided with a connection socket; the act of sliding the iron on the heat insulated plate automatically connects the heat element with the electric current, without any effort on the part of 30 the ironer or the use of switches. With each rest plate is furnished a standard cord and plug that is not in any way subject to wear or hard usage, being independent of the iron and the iron's movements—it will give a lifetime service. The 40 rest plate is simple and durable in construction, making it practically indestructible. It is made of metal that will not rust or show wear and it can be attached and readily detached from the ironing board. 45

I claim:

1. In combination, a hand iron containing an electrical heating element, a heel having terminal plugs for said element, a fixed housing having a wall provided with terminal devices 50 adapted to receive said plugs and to be connected to a supply circuit, said wall having an opening adapted to be closed by said heel when the plugs and the terminal devices are connected, and thermostatic means in the housing adapted to open 55 the circuit at a predetermined temperature.

2. The combination claimed in claim 1, in which the housing is provided with another wall having an opening whereby when the iron is removed from the housing after a period of heating 60 the interior of the housing cools rapidly and the thermostatic means quickly restores the circuit to closed condition.

3. The combination claimed in claim 1, including multiple terminal devices in the housing with 65 which the plugs of the iron are adapted to contact asynchronously, and including resistance means in the circuit first completed adapted to be shunted out upon completion of the second circuit, the housing terminals and the plugs on the iron being so arranged that the heel of the iron closes 70 the opening in the housing only when the second circuit is completed.

4. The combination of an iron containing within it an electrical heating element with a pair of 75

terminal plugs for said heating element mounted on and insulated from the heel of the iron, a stand for said iron, a housing on said stand, power circuit terminals mounted on said housing and two pairs of terminals adapted to receive the said plugs on the iron, said terminals being arranged so that the plugs will engage first one pair and then the other pair when the iron is placed on the stand, and conversely will disengage from

one pair before the other when the iron is removed from the stand, both of said pairs of terminals connected serially to the power terminal on the housing, and resistance included in the circuit between the power terminals and the pair of contacts which are first engaged in closing and last engaged in opening the heating circuit on the iron in removing the same from the stand. ⁵
